UNITED STATES PATENT OFFICE.

ORVELLAS H. GILBERT, OF CHICAGO, ILLINOIS.

IMPROVEMENT IN DOOR-LATCHES.

Specification forming part of Letters Patent No. 177,933, dated May 30, 1876; application filed April 1, 1876.

To all whom it may concern:

Be it known that I, ORVELLAS HENRY GILBERT, of Chicago, in the county of Cook, and State of Illinois, have invented a new and useful Improvement in Door-Latch Bolts and Locks; and I do hereby declare the following to be a full, clear, and exact description thereof, which will enable others skilled in the art to which my invention relates to make and use the same, reference being had to the accompanying drawing forming part of this specification, in which—

Figure 1 is inside view of lock. Fig. 2 is a perspective view of rose, escutcheon, knob, and lever; Fig. 3, cross-section.

In the accompanying drawing, A represents my improved lock; A', the latch-bolt, provided with the slot or mortise B. d is a spiral spring, one end bearing against the lug d' attached to the case of the lock, and the opposite end bearing against the lug b, projecting from the latch-bolt. B' is a key-bolt provided with a slot upon its lower end to allow it to work vertically on the pin b'. C is a tumbler, one end pivoted to the key-bolt, and the opposite end provided with a mortise, c, upon each side of which are projections, c'. C' is a rose provided with the slot d, through which passes the lever D. D' is the shank, and D'' the knob.

It will be observed that the rose, the shank, and the key escutcheon are all cast in one piece. The lever is then placed in position in the mortise, and the pin or screw d' passed through the lips on each side of the mortise, and through the lever, to hold it in position. After the lock is placed in position in the door the ends of the levers D are placed in the mortise B in the end of the bolt A', and the rose is then secured to the door, the screws entering the door above and below the lock,

which operation secures the key-hole escutcheon and the knob at the same time.

It will also be observed that the knob is secured to the outer end of the shank, the washer b'' forming the shoulder against which it rests. In opening the door the knob does not turn as in ordinary locks. The hand, coming in contact with the lever D, presses the same toward the shank. The opposite end strikes the end of the mortise B, and moves the bolt in that direction enough to cause it to be disengaged from the casing and allow the door to open. When the hand is released the spring a throws the bolt back to its original position.

A lock constructed in this manner obviates the liability of the knobs becoming loose, and the wear of the spindle in ordinary locks, which causes them to rattle.

When locking the door, the key is inserted in the key-hole in the ordinary manner, and the key-bolt thrown behind the rear end of the latch-bolt, which secures it in a firm manner.

Having thus described my invention, what I claim as new, and desire to secure by Letters Patent, is—

The stationary knob-shank D', and rose-plate C', cast in one piece, and provided with mortise B, in combination with projecting lips and lever D passing through a mortise, B, in the latch-bolt A, and pivoted to said rose-plate, substantially as and for the purposes specified.

The above specification signed by me this 9th day of March, 1876.

ORVELLAS H. GILBERT.
